UNITED STATES PATENT OFFICE

162,481

WALLPAPER

James Seeman, New York, N. Y.

Application October 13, 1950, Serial No. 12,547

Term of patent 7 years

(Cl. D59—10)

To all whom it may concern:

Be it known that I, James Seeman, a citizen of the United States of America, residing in New York, county of New York, and State of New York, have invented a new, original, and ornamental Design for a Wallpaper, of which the following is a specification, reference being had to the accompanying drawing, forming part thereof.

The figure shows a surface view of a wallpaper, showing my new design.

The broken lines indicate a design unit which repeats vertically on the drawing as indicated.

I claim:

The ornamental design for a wallpaper, substantially as shown and described.

JAMES SEEMAN.
